UNITED STATES PATENT OFFICE

FRANK TENCH, OF LONDON, ENGLAND, ASSIGNOR, BY MESNE ASSIGNMENTS, TO ASSOCIATED TELEPHONE & TELEGRAPH COMPANY, OF KANSAS CITY, MISSOURI

TELEPHONE SYSTEM

Application filed August 9, 1926, Serial No. 128,016, and in Great Britain October 13, 1925.

The present invention relates to telephone systems and is more particularly concerned with systems in which battery for speaking purposes is supplied in the direction of the called party rather than in the direction of the calling party, that is to say, it is supplied from the first numerical switch in the exchange or, in the case of an inter-exchange call, from the first switch of the train in each exchange. The invention moreover is particularly applicable to a system in which the impulses for setting the automatic switches are sent in a circuit including the two speaking leads in series while the supervisory signals are subsequently transmitted over the speaking leads independently and it may therefore be considered as a development of the system shown in Patent No. 1,672,225, issued June 5, 1928.

20 The main feature of the invention consists in the modification of the arrangement above referred to in such a manner that the source of energy for dialling purposes is located at the outgoing end of the trunk line rather than at the incoming end as has been usual hitherto. This arrangement is found in practice to give improved operating conditions and also enables a number of simplifications to be made in the circuits. The new arrangement 25 retains the feature of the previous invention that the supervisory relays are not connected up or used for any purpose until all the dialling has been done and there is therefore no danger of these relays being operated prematurely and thus causing, for instance, false metering.

According to one feature of the invention, battery and earth are fed forwards from the first numerical switch in an exchange over 30 the two speaking leads respectively during dialling through non-supervisory equipment and are fed forwards on the completion of dialling through one or more supervisory relays.

45 According to another feature of the invention the line relay of an incoming selector is connected directly across the speaking leads without any battery or earth connections when the switch is in normal position and 50 during the impulsive period, while after the

termination of impulse sending it is connected to one speaking lead only.

A further feature of the invention is that in a telephone system having arrangements for sending selective supervisory signals 55 under the control of a plurality of supervisory relays adapted to be connected to a single lead, when supervisory signals are to be transmitted the supervisory relays are connected up automatically in turn.

60 The invention will be better understood from the following description of a preferred embodiment taken in conjunction with the accompanying drawings. It will be understood however that the system shown is given 65 by way of example only and that detail modifications could be made by those skilled in the art without exceeding the scope of the invention.

Referring now to the drawings, these show 70 by means of the usual circuit diagrams the arrangements of the various switches which may be used in setting up a connection.

Fig. 1 is a first selector arranged to feed battery to the calling party and also forward 75 in the direction of the called party.

Fig. 2 is an incoming selector accessible over a two-conductor trunk and also arranged for battery feeding purposes.

Fig. 3 is an intermediate selector, and 80

Fig. 4 is a connector or final selector.

Figs. 5 and 6 show the arrangements for setting up manual to automatic calls with a special operator's selector, embodying the 85 principles of the invention.

Fig. 7 shows the apparatus at an incoming operator's position, together with a portion of a cord circuit arranged to work in conjunction therewith, and

Fig. 8 shows a desirable modification of 90 the main circuit principles which is applied to an incoming selector, but, it will be understood, could equally well be applied also to a first selector.

A complete connection will first be traced 95 including Figs. 1, 2, 3 and 4, the switches shown being assumed to be taken into use in that order. The first selector in Fig. 1 is accessible from a subscriber's rotary line switch in the usual manner. When this 100

switch is seized, a circuit is completed for the line relay 5 over conductors 1 and 2 and the subscriber's loop. Relay 5 upon operating, at armature 7 completes a circuit for relay 8 and at armature 6 prepares a circuit for repeating impulses to succeeding switches. Upon operating, relay 8 at armature 9 connects earth to release trunk conductor 3 so as to hold the line switch operated and at armature 10 opens the circuit of release magnet 12 and prepares the impulsive circuit. The earth connection to release trunk conductor 3 is extended by way of back contact and armature 31 to the upper winding of relay 17, which is thereupon operated. At armature 19 it cuts out the retard 18 and substitutes a low non-inductive resistance so as to give improved impulsive conditions, at armature 20 prepares a locking circuit for itself over its upper winding, and at armature 21 prepares a locking circuit over its lower winding, at the same time opening a point in the circuit of the supervisory relays 36 and 40.

No further changes take place until the subscriber dials the first digit in the wanted number, whereupon a corresponding number of interruptions are produced in the circuit of line relay 5. Upon each release of relay 5, a circuit is completed from earth, armature 7 and its back contact, armature 10 and its front contact, winding of relay 13 to battery and parallel thereto by way of armature 33 and its back contact, vertical magnet 35 to battery. The vertical magnet is accordingly operated to raise the switch wipers a corresponding number of steps and relay 13 is energized, and by virtue of its slow-to-release characteristic remains operated throughout the train of impulses. Relay 13 at armature 15 completes a locking circuit for relay 17 over its upper winding, and at armature 16 short-circuits the lower winding of relay 17, which operation is however without useful effect at this time. Relay 13 also at armature 14 prepares a circuit for relay 22 which is completed as soon as the switch steps off-normal, and extends as follows: earth, front contact and armature 9, armature 14 and its front contact, back contact and armature 30, interrupter contacts 26 of the rotary magnet 25, off-normal contacts 27, winding of relay 22 to battery. Relay 22 upon operating, at armature 23 prepares a circuit for the rotary magnet and at armature 24 completes a locking circuit for itself. At the end of the series of impulses, relay 13 de-energizes, thereupon at armature 14 and its back contact completing a circuit for rotary magnet 25, whereupon the switch wipers are rotated into engagement with the first set of bank contacts in the level to which they have been raised. Near the end of its stroke rotary magnet 25 opens the interrupter contacts 26, thereby opening the circuit of relay 22 which

accordingly de-energizes and at armature 23 opens the circuit of the rotary magnet, which de-energizes also. In case the set of contacts with which the wipers are now in engagement extend to a line which is in use, test wiper 44 will engage an earthed contact, and a circuit will again be completed for stepping relay 22, which therefore energizes and causes the rotary magnet to advance the wipers a further step, whereupon both relay 22 and magnet 25 are again de-energized. This alternate operation of relay 22 and magnet 25 continues until test wiper 44 no longer finds earth, whereupon switching relay 28 is no longer short-circuited and energizes in series with relay 22, which is however not now energized owing to the high resistance of relay 28. The operation of relay 28 at armatures 29 and 34 switches the speaking conductors through, at armature 30 connects earth to wiper 44, to busy the seized line, at armature 31 opens the initial energizing circuit of relay 17, at armature 32 prepares the circuit of the supervisory relays 36 and 40 and at armature 33 opens a point in the circuit for the vertical magnet 35 so as to prevent this magnet from being operated by subsequent trains of impulses. Relay 17 does not de-energize at this time in spite of the fact that the circuit over its upper winding is opened, since a holding circuit is now completed as follows: battery, armature 19 and its front contact, front contact and armature 6, front contact and armature 29, wiper 45 and the contact with which it is in engagement, conductor 51 extending to the incoming selector, (Fig. 2), winding of line relay 53, normally closed springs controlled by armature 69, armature 79 and its back contact, conductor 52, contact engaged by wiper 46 and said wiper, armature 34 and its front contact, armature 21 and its front contact, lower winding of relay 17 to earth. Relay 17 accordingly remains energized in this circuit and relay 53 also operates, and at armature 55 completes a circuit for slow relay 56. The operation of relay 56 prepares the operating circuit of the switch in the usual manner at armature 58, and at armature 57 completes a circuit which extends from earth over back contact and armature 77, upper winding of relay 64 to battery. Relay 64 upon operating performs similar functions to relay 17 in the first selector, namely, at armature 66 cuts out the retard 65, at armatures 67 and 68 prepares locking circuits by way of its upper and lower windings respectively and at armature 69 completes an auxiliary circuit for relay 53 independent of armature 79.

When the subscriber dials the next series of impulses, corresponding interruptions are again produced in the circuit of relay 5, which accordingly operates its armatures 6 and 7. The operation of armatures 7 again effects the energization of relay 13 throughout the

train of impulses, and this relay by operating its armature 15 completes a locking circuit for relay 17, so as to maintain this relay energized during the train of impulses while its lower winding is short-circuited at armature 16 so as to improve the impulsive circuit. Relay 5 also at armature 6 interrupts the circuit of relay 53 and this accordingly de-energizes correspondingly and completes a circuit by way of armature 80 and its back contact for vertical magnet 96. Relay 60 is energized throughout the train of impulses in parallel with vertical magnet 96 and at its armature 61 prepares a circuit for stepping relay 70 which becomes effective when the off-normal contacts close on the first vertical step of the switch. When relay 60 de-energizes a circuit is completed over armature 61 and its back contact, and armature 72 and its front contact for rotary magnet 71 so that the switch takes one step and the operation of the interrupter contacts then open the locking circuit of relay 70 over armature 73. The hunting motion of the switch then takes place in the same manner as was described in connection with the first selector (Fig. 1) and when test wiper 91 no longer finds earth, switching relay 74 operates in series with stepping relay 70, which latter is however not now operated. Relay 74 at armatures 75, 76 and 81 connects the wipers 91, 92 and 93 through, at armature 77 opens the initial energizing circuit of relay 64, at armature 78 prepares the circuit for the supervisory relays 82 and 87, at armature 79 opens the original circuit for line relay 53 and prepares a new circuit and at armature 80 opens a point in the circuit of vertical magnet 96 so as to prevent any subsequent operation of this magnet.

It will be assumed that the connection is then extended to the intermediate selector shown in Fig. 3 and consequently when switching through takes place, a circuit may be traced as follows: battery, armature 66 and its front contact, front contact and armature 54, front contact and armature 75, wiper 92 and the contact with which it is in engagement, lead 101, normally closed springs controlled by armature 117, winding of line relay 104, lead 102, contact engaged by wiper 93 and said wiper, armature 81 and its front contact, armature 68 and its front contact and the lower winding of relay 64 to earth. Relay 64 is therefore maintained energized in spite of the opening of its initial circuit, and moreover relay 104 in the intermediate selector is operated, and by attracting its armature 105 completes a circuit for release relay 106. The latter energizes in its turn and at armature 107 prepares the switch for operation in the usual manner, at the same time opening a point in the circuit of release magnet 108.

When the subscriber dials the succeeding

digit, interruptions are produced in the circuit of relay 5 as before, and these are again repeated at contact 6 to relay 53. Armature 54 of this relay is now effective to repeat these impulses to line relay 104 of the intermediate selector. Relays 13 and 60 operate as before to short-circuit the lower windings of relays 17 and 64, while at the same time completing locking circuits for the upper windings of these relays. Upon each de-energization of relay 104, a circuit is completed from earth, back contact and armature 119, armature 105 and its back contact, armature 107 and its front contact, winding of relay 109, winding of vertical magnet 111 to battery. By the operation of magnet 111 the switch wipers are raised a number of steps corresponding to the digit dialled, and relay 109 is energized and, being slow, remains energized throughout the train of impulses. Stepping relay 112 is energized as usual when the off-normal contacts close upon the first vertical step of the switch, and when relay 109 de-energizes, a circuit is completed by way of armatures 110 and 114 for rotary magnet 115. The hunting motion of the switch then proceeds in known manner and upon a free trunk being found, relay 116 operates and at its armatures 117, 118 and 120 connects its wipers through. Moreover at armature 119 the circuit of relay 106 is opened, and at armature 117 the circuit of relay 104 so that both these relays de-energize.

Assuming that the system being described is a 5 digit one having a maximum capacity of 100,000 lines, the connection will now be extended to a connector, for instance that shown in Fig. 4. The circuit for maintaining relay 64 now extends over wiper 122, lead 141, winding of line relay 144, armature 160 and its back contact, armature 170 and its back contact, lead 142, wiper 123, and over the previously traced circuit through the lower winding of relay 64 to earth. Relay 144 now energizes and at armature 145 completes a circuit for release relay 146 and this in its turn energizes to prepare the switch for operation in known manner.

When the next series of impulses is dialled, the interruptions are repeated by relays 5 and 53 as previously described and relay 144 accordingly de-energizes intermittently. Upon the first release of relay 144 a circuit is completed as follows: earth, armature 171 and its back contact, armature 145 and its back contact, armature 148 and its front contact, off-normal spring 149 and its resting contact, winding of relay 152, winding of vertical magnet 154 to battery. As soon as the switch takes its first step however, the off-normal springs shift and the succeeding impulses, if any, are transmitted by way of armature 148 and its front contact over spring 149 and its working contact, armature 153 and its front contact and through the

winding of relay 152 as before, this relay having been energized by the first impulse. The switch wipers are thus stepped up in the usual manner, relay 152 remaining energized throughout this operation. When the series of impulses terminates, relay 152 falls away and consequently when the succeeding and last series of impulses operates relay 144, the impulsing circuit extends over armature 153 and its back contact, back contact and armature 162, armature 173 and its back contact, winding of rotary magnet 167 to battery and parallel thereto, winding of relay 163 to battery. The switch wipers are therefore rotated a number of steps corresponding to the digit dialled and relay 163 remains energized throughout this train of impulses. Relay 163 at its armatures 164 and 166 shuts armatures 160 and 162 respectively and their back contacts so as to prevent circuits being broken prematurely in case busy relay 159 should be energized owing to the wipers rotating over busy contacts.

It will be assumed in the first instance that the wanted party is idle at this time; consequently when test wiper 175 comes to rest on the contact associated with his line, it will not find earth and the busy relay 159 if previously energized will now de-energize. An instant afterwards, relay 163 de-energizes and a circuit is then completed from earth, front contact and armature 147, armature 161 and its back contact, upper winding of the relay 168, back contact and armature 165, test wiper 175 and by way of the cut-off relay and rotary magnet of the subscriber's line switch to battery. Relay 168 and the cut off relay energize in series in this circuit but owing to the well-known inter-locking arrangement between the line and cut-off relays, the later relays is only able to operate its armatures sufficiently to clear the line of its normal battery and earth connections, but not sufficiently to connect up the wipers of the line switch. Relay 168 upon operating, at armatures 169 and 174 connects up its wipers so that ringing current from the lead RM is projected out over the called line, returning by way of armature 156 and its back contact and the upper winding of the ringing trip relay 155 to battery. Relay 168 also at armature 171 connects earth to test wiper 175 to busy the line, at armature 172 completes a locking circuit for itself by way of its lower winding, at armature 173 opens a point in the impulsing circuit to prevent any further operation of the rotary magnet in case the subscriber should dial again, and at armature 170 opens the circuit of line relay 144, at the same time connecting up ringing induction by way of the small condenser 176.

The effect of the opening of the circuit of line relay 144 is to open also the circuit of relay 64 of the incoming selector and this relay accordingly de-energizes, thereby at its

armatures 67 and 68 opening points in its locking circuits so that it cannot be again energized (armature 77 being now operated), and at armature 68 also connecting up the supervisory relays 82 and 87. Moreover at armature 69 the circuit of relay 53 is altered so that it is now connected below one speaking lead and earth at armature 79 instead of across the two speaking leads. The effect of this is to open the circuit of relay 17 in the first selector and this de-energizes with somewhat similar results, the most important of which is the connecting up of the supervisory relays 36 and 40.

The circuits remain in this condition until the called party replies, whereupon in consequence of the direct current bridge across the speaking leads, the ringing trip relay 155 is operated, thereupon at armature 157 completing a locking circuit for itself, and at armatures 156 and 158 disconnecting ringing current and switching the speaking leads through. A circuit is now completed as follows: battery, retard 65, normally closed springs controlled by armature 66, front contact and armature 54, front contact and armature 75, wiper 92, lead 101, front contact and armature 117, wiper 122, lead 141, front contact and armature 156, armature 169 and its front contact, wiper 177, over the called party's loop, wiper 178, front contact and armature 174, armature 158 and its front contact, lead 142, wiper 123, armature 120 and its front contact, lead 102, wiper 93, armature 81 and its front contact, armature 68 and its back contact, armature 78 and its front contact, lower winding of relay 82, winding of relay 87 to earth. Since the call has been made to another automatic subscriber, the resistance of this circuit is such that both relays 82 and 87 now operate the former at armature 83 completing a locking circuit for itself over its upper winding and at armature 84 short-circuiting the high resistance 86. Relay 87 upon operating, at armature 90 completes a point in an auxiliary circuit for relay 56, another point in which however has previously been opened at armature 85, at armature 89 short-circuits the lower winding of relay 82 so as to give standard talking conditions in every case and at armature 88 connects battery through the retard 97 to conductor 52. The battery connection over lead 52 is extended by way of wiper 46, armature 34 and its front contact, armature 21 and its back contact, armature 32 and its front contact, winding of relays 36 and 40 to earth. Since the high resistance 86 has been cut out, both these relays are able to operate, the former locking itself up at armature 37 and at armature 39 connecting earth to the metering conductor 4 so that the successful call is charged against the calling party. The operation of relay 40 closes a point in an auxiliary circuit for relay 8 at armature 42 and

at armature 41 short circuits the energizing winding of relay 36.

The subscribers may now converse as desired and when they have finished they will both replace their receivers. When the receiver is replaced at the called sub-station, relay 87 de-energizes and opens the circuit of relay 40, which de-energizes in its turn, but this operation produces no particular effect, though it will be appreciated that relay 40 could be arranged to control a lamp associated with the switch and thus notify an attendant, particularly of the condition in which the called party had replaced his receiver but the calling party had omitted to do so. When the calling party replaces his receiver, relay 5 de-energizes and at armature 7 opens the circuit of relay 8, which de-energizes in its turn after a short interval, thereby at armature 9 opening the circuits for relays 28 and 36 and the switching relay of the line switch. Moreover at armature 10 the circuit for the release magnet 12 is completed over off-normal springs 11 and this magnet operates to restore the switch to normal. Line relay 5 furthermore at armature 6 opens the circuit for line relay 53 and this de-energizes, thereby opening the circuit for relay 56. When this in its turn falls away, the circuit for release magnet 59 is completed, and the incoming selector is restored to normal. Moreover at armature 57 earth is removed from the release trunk conductor extending to the intermediate selector and connector, and this has the effect of bringing down relays 74, 82, 116, 155 and 168. Both these switches are then restored to normal by the operation of their respective release magnets 108 and 151, the circuit for the latter extending from earth, armature 171 and its back contact, armature 145 and its back contact, armature 148 and its back contact, off-normal springs 150, winding of magnet 151 to battery. The whole connection has now been released and the switches used therein may be employed in setting up another connection.

Consider now the case in which the called party was busy when the connector wipers came to rest on his line; in these circumstances wiper 175 will find earth, consequently busy relay 159 will be operated. Thereupon at armature 162 it opens a point in the impulsing circuit to prevent further operation of relay 163 or rotary magnet 167, at armature 161 prepares a locking circuit for itself and at armature 160 disconnects line relay 144 and connects up busy tone and intermittent battery through a high resistance by way of the lead BT. An instant later relay 163 deenergizes and a locking circuit is then completed for the busy relay to earth at armature 147 and armatures 160 and 162 become effective having previously been shunted by armatures 164 and 166. Owing to the opening of the circuit of relay 144, as

in the case when the subscriber was idle and relay 168 operated, relay 64 in the incoming selector is now de-energized and connects up the supervisory relays 82 and 87. Owing to the inclusion of the high resistance in the busy flash battery circuit, relay 82 is unable to operate in this case, but relay 87 operates and hence each time battery is connected up repeats back the connection of battery by way of retard 97 at its armature 88, but in this case through the high resistance 86. The release of relay 64 opens the circuit for relay 17 and as before, this relay connects up relays 36 and 40, but in this case relay 40 only can operate and consequently no metering takes place. As it is assumed that only a subscriber will have access to a selector of the type shown in Fig. 1, the busy flash battery is in this case without effect and the subscriber hears busy tone, which is transmitted through the various talking condensers. Accordingly he hangs up his receiver in due course and the whole connection is then released in the manner previously described.

It may be mentioned at this point that in case any of the selectors used in setting up the connection should be rotated to the eleventh position owing to all trunks in the desired level being busy, the appropriate switching relay would be operated but since the wipers are then disconnected, no maintaining circuit would be completed for the relay, such as 17 or 64. Consequently this relay deenergizes and effects the change from impulsing to supervisory conditions so as to permit of the busy signal being transmitted back. Moreover the cam springs indicated at 43, 94 and 124 in Figs. 1, 2 and 3 respectively are operated and busy tone and intermittent battery through a high resistance are connected to the lower speaking conductor. Inasmuch however as the first selector, Fig. 1 will not be taken into use from an operator's position, only busy tone need be connected up at springs 43 since no provision need be made for flashing an operator's supervisory lamp.

Consider now the case in which a subscriber wishes to extend a call to an operator's position, for instance, for information or inquiry. It will be assumed for convenience of description that the switches shown in Figs. 1, 2 and 3 are again employed and that the switch in Fig. 3 when raised to a particular level has access to apparatus at an operator's position such as that shown in Fig. 7. It will be understood of course that in practice access might quite well be obtained to the operator's position direct from the bank of the first selector, but with the arrangement above suggested a more complete description is possible of the arrangement of the various switches.

When the call is initiated and impulses are

sent out, the operation of the switches shown in Figs. 1, 2 and 3 takes place in the manner above described so that this need not be again considered in detail. When the intermediate selector, Fig. 3, switches through by the operation of relay 116, a circuit is completed as follows: battery, armature 66 and its front contact, front contact and armature 54, front contact and armature 75, wiper 92, lead 101, 10 front contact and armature 117, wiper 122, lead 301, winding of relay 303 to earth. Relay 303 is operated in this circuit and at its armature 305 completes a circuit for the calling lamp 314 and at its armature 304 connects up ringing induction by way of lead 312 so as to inform the calling party in the same way as on a call to an automatic subscriber that the operator is being signalled. A further effect of the switching-through action 15 of relay 116 is to open the circuit of relay 64 since there is at present no battery connection to lead 302 and this relay, upon de-energizing, establishes supervisory conditions in the incoming selector and by opening the circuit of relay 17 brings down this relay also which establishes supervisory conditions in the first selector. The operator, upon noting the lighted condition of the lamp 314, will insert the plug of an idle cord circuit in the appropriate jack, thereupon completing a circuit for the sleeve relays 308 and 315 in series. Both these relays then operate and the latter at armature 316 lights the supervisory lamp 319 associated with the cord circuit. 20 The operation of relay 308 at armature 311 extinguishes the calling lamp 314 and at armature 310 connects the impedance 313 across the jack springs and cuts off the ringing induction. Assuming that the calling party is 25 still on the line so that relay 303 remains operated, a circuit is now completed for the supervisory relays 317 and 320 in series by way of the repeating coils in the cord circuit and impedance 313, and relay 317 by operating its armature 318 extinguishes the supervisory lamp 319. Relay 308 also at armature 309 connects battery to conductor 302 through the retard 306 and the high resistance 307. The effect of this is to energize supervisory 30 relay 87, but in view of the inclusion of resistance 307 in the circuit, marginal relay 82 is unable to operate at this time and consequently retard 97 is connected to conductor 52 through the high resistance 86. It will 35 be noticed that since armature 90 is now operated, while armature 85 is not operated, an auxiliary circuit is completed for release relay 56, this constituting the operator's hold-up feature. The connection of high resistance battery to lead 52 in a similar manner produces the energization of relay 40, but not of relay 36, and as the completion of the metering circuit is dependent only on relay 36, it is clear that no metering can take place 40 in this case. Moreover at armatures 38 and

42 an auxiliary circuit is completed for the release relay 8 similar to that which was completed for release relay 56 of the incoming selector.

The subscriber may now make his inquiry or complaint and when he has finished he will replace his receiver. The effect of this is to de-energize relay 5, which at its armature 7 opens the initial circuit of relay 8, but as previously pointed out this relay is now maintained over the auxiliary circuit. At armature 6 however the circuit for line relay 53 in the incoming selector is opened and this de-energizes, thereby opening the initial circuit of relay 56, which relay however is held up under the control of the operator. At armature 54 the circuit for relay 303 is opened and this upon de-energizing, at armature 304 opens the loop across the jack springs, thereby bringing down relay 317. 45 At armature 318 a circuit is now completed for the lamp 319, thus giving the operator clearing supervision. When she takes down the connection by removing the plug from the jack, relay 308 is de-energized and at armature 309 the circuit for relay 87 is opened. Consequently relay 56 is now de-energized and the switch is restored in the usual manner, the removal of earth at armature 57 from the release trunk conductor 103 initiating the release of the intermediate selector as previously described. In a similar manner the first selector in Fig. 1 is restored to normal upon the release of relay 40 and subsequently relay 8. 50

The case must now be considered in which a connection is set up from a manual subscriber to an automatic subscriber, for instance by way of the operator's position and operator's selector shown in Figs. 5 and 6. 55 When the subscriber removes his receiver, his line relay is energized in the usual manner and the calling lamp is lighted; the operator thereupon inserts the plug P^1 into the jack J^1 , thus operating the cut-off relay to remove the normal battery and earth connections from the line. The operator then throws her speaking key and ascertains the calling party's requirements and then inserts the calling plug P^2 into a jack such as J^2 associated with a free outgoing trunk line. The sleeve relay 204 is thereupon operated in series with the supervisory lamp 210, and relay 204 at armature 205 lights the lamp 206 to indicate that the trunk is busy. The insertion of the plug P^2 has no effect however at present on the operator's selector, this arrangement being adopted in order to preclude the possibility of the operator sending a false impulse, particularly if she inserts the plug carelessly. 60

When she throws her dialling key, however, preparatory to dialling the wanted number, a circuit is completed as follows: battery, closed off-normal springs 202 of the dial, impulse springs 203, working contact and

spring 200 of the dialling key K, tip of plug P², tip spring of jack J², conductor 251, back contact and armature 281, normally closed springs controlled by armature 269, winding of relay 253 to earth. Relay 253 operates in this circuit: at armature 254 completes a circuit for relay 256 and at armature 255 prepares a circuit for repeating impulses to succeeding switches. Upon operating, relay 256 at armature 258 prepares the impulsive circuit and at armature 257 completes a circuit as follows: earth, front contact and armature 257, back contact and armature 278, upper winding of relay 265 to battery. Relay 265 thereupon at armatures 266 and 267 prepares locking circuits for itself, at armature 268 connects up battery to replace that which will be removed from spring 202 during dialling, at armature 269 completes a circuit for relay 253 independently of armature 281 and at armature 270 substitutes a low-non-inductive resistance for the retard 264. The switch is now in condition to receive dialled impulses and the operator manipulates the dial in accordance with the first digit of the wanted number, thereby producing a number of interruptions in the circuit of line relay 253. Each time this relay de-energizes, a circuit is completed over armature 279 and its back contact for vertical magnet 283, and also for the slow relay 260, which is therefore maintained operated throughout the train of impulses. Only armature 261 of relay 260 performs any useful function at this time and this at its front contact prepares a circuit for stepping relay 271, which is completed as soon as the off-normal contacts close on the first step of the switch. Relay 271 in known manner at armature 272 prepares a circuit for rotary magnet 273 and at armature 274 completes a locking circuit for itself. When relay 260 de-energizes at the end of the train of impulses, the circuit for rotary magnet 273 is completed and the switch wipers are rotated one step. The rotary magnet now interrupts the circuit of stepping relay 271 and the switch subsequently hunts to find a free outgoing trunk in a manner which is well understood. When such a trunk is found, switching relay 275 operates in series with stepping relay 271 and at its armatures 276, 277 and 282 connects its wipers through. Moreover at armature 278 it opens the initial energizing circuit of relay 265, at armature 279 opens a point in the circuit of vertical magnet 283 so as to prevent any further operation of this magnet, at armature 280 prepares a circuit for connecting up supervisory relay 284, and at armature 281 opens the initial circuit of relay 253. Relay 265 is now held operated over its lower winding, front contact and armature 267, front contact and armature 282, line relay of the succeeding switch, which may be assumed to be an intermediate selector similar to that

shown in Fig. 3, armature 276 and its front contact, front contact and armature 255, front contact and armature 270 to battery. When succeeding trains of impulses are dialled, relay 253 is again operated intermittently and at its armature 255 repeats these impulses to the particular switch ahead which is to be operated. Relay 260 is operated during each train of impulses and at armature 263 short-circuits the lower winding of relay 265 so as to improve the impulsive conditions, but at armature 262 completes a locking circuit for the upper winding of relay 265 so that this relay is maintained operated.

When the connection has been completely set up or a busy condition has been encountered, the maintaining circuit for the lower winding of relay 265 is opened and this relay de-energizes, thereby connecting up supervisory relay 284. This relay is then operated in a manner similar to that previously described, when the called party replies, and at its armature 285 connects up retard 286 to lead 251. This battery connection is extended over spring 200 of the dialling key and its resting contact (since it has now of course been restored), upper righthand winding of the repeating coil, winding of relay 207 to earth. Relay 207 is therefore operated and at its armature 209 short-circuits lamp 210, thus giving the operator answering supervision. It will be noted that in the operator's selector only one supervisory relay 284 need be provided, since the operator herself effects the metering and is able to determine whether a call is to be charged to the calling party or not. When both subscribers have replaced their receivers, lamps 210 and 211 in the cord circuit will both light and the operator will then take down the connection, whereupon all the apparatus will be released in the usual manner. It will be noticed that if a busy condition is encountered the intermittent battery connection will energize relay 207 intermittently and thus cause lamp 210 to flash.

A description will now be given of a modified form of the invention which is shown in Fig. 8 as applied to an incoming selector. It will be understood of course that similar modifications could be made to the other battery-feeding switches but detailed circuits for these have not been shown, since the required modifications will be sufficiently obvious to those skilled in the art from a full description of an incoming selector only. It will be assumed in what follows that the switch shown in Fig. 8 fits into the switch train in place of that shown in Fig. 2. When the switch is taken into use from the first selector Fig. 1, a circuit is completed from the pulsing battery over armatures 19 and 6 for line relay 353, which circuit extends over the normally closed springs controlled by armature 372 and armature 391 and its back contact, and

as before includes the lower winding of relay 17. Relay 353 therefore operates and at armature 255 completes a circuit for relay 356 and at armature 354 prepares the impulse repeating circuit. Relay 356 prepares the switch for operation in the usual manner and at armature 357 completes a circuit over armature 390 and its back contact for the upper winding of relay 366. Relay 366 upon operating, in addition to performing the same functions as relay 64 in the incoming selector, Fig. 2, at armatures 367 and 373 disconnects one terminal of the talking condensers 396 and 397 to prevent their exercising any deleterious effect on the impulsing, and moreover at armature 370 prepares the usual circuit for relay 361 which is energized during each train of impulses.

When the first digit is sent to the incoming selector, relay 353 de-energizes intermittently in the usual manner and completes circuits for relay 361 and vertical magnet 394 in parallel. Upon the termination of the series of impulses, relay 361 falls back and at armature 362 the usual circuit is completed for initiating the hunting operation which takes place owing to the interaction of stepping relay 383 and rotary magnet 386. When a free trunk is found, switching relay 387 is operated and at armatures 388, 389 and 393 connects up the switch wipers. At armature 392 the vertical magnet is definitely cut off, at armature 391 a new circuit is prepared for relay 353 and at armature 390 the initial energizing circuit of relay 366 is opened and a further circuit is prepared for relay 361. Subsequent series of impulses are repeated at armature 354 and relay 361 is energized throughout each train, thereby at armature 363 short-circuiting the lower winding of relay 366, at armature 364 completing a locking circuit for this relay by way of its upper winding and at armature 365 altering the connections of the supervisory relays, though at this time without useful effect.

When all the impulse sending has taken place, the maintaining circuit over the lower speaking conductor for relay 366 is opened and this relay de-energizes, thereby at armatures 367 and 373 connecting the speaking leads through and at armature 370 completing a further circuit for relay 361, which extends as follows: earth, front contact and armature 357, armature 390 and its front contact, armature 376 and its back contact, back contact and armature 370, winding of relay 361 to battery. Relay 361 upon operating at this time, connects the lower winding of relay 374 to the lower speaking lead. The de-energization of relay 366 also at armature 372 opens the circuit of relay 17 in the first elevator so that supervisory conditions are established thereat in the manner previously described.

65 The circuits remain in this condition while

ringing is taking place, and when the called party removes his receiver, a loop is completed over the two speaking leads in series from battery by way of retard 360 returning by way of armature 371 and its back contact, front contact and armature 365, winding of relay 374 to ground. It should be mentioned that in this instance relay 374 is arranged to pull up on connections of all classes, while relay 380 is marginal and only energizes when its circuit does not include a high resistance, that is to say, in the case of calls to automatic subscribers. Hence relay 374 now operates whether the call has been extended to a subscriber or to an operator, and at armature 375 completes a locking circuit for itself over its upper winding, at armature 377 connects battery through retard 395 to lead 352, whence it is extended back to the supervisory relays in the first selector. Relay 374 moreover at armature 376 opens the circuit of relay 361, which accordingly de-energizes after a short interval. When this occurs the lower winding of relay 374 is cut out and the winding of relay 380 is substituted. In case therefore the connection has been extended to a subscriber, relay 380 will be able to operate and at armature 381 will short-circuit the high resistance 379 so as to repeat back the supervisory conditions to the previous switch. Thus it will be seen that each of the supervisory relays is connected to the line alone in turn, and by this means it is possible to obtain a better operating margin so as to give improved reliability. The release of the switch takes place under the control of the calling party in the usual manner, since unless the operator's hold feature represented by the auxiliary circuit for relay 356 over armatures 378 and 382 is in operation, when relay 353 de-energizes, relay 356 is also released. Thereupon at armature 358 it completes a circuit for the release magnet 359 and at armature 357 removes earth from the release trunk conductor so as to release the succeeding switches under its control.

The modification of the supervisory relay connections just described was devised to overcome a difficulty sometimes experienced under adverse conditions in obtaining complete reliability of operation with a non-marginal and a marginal relay in series. The arrangement in the main patent and in the system described herein with the exception of Fig. 8 is that on a call to a subscriber, when both supervisory relays are to operate and metering is to take place the circuit for the relays extends over both speaking leads in series, whereas when only the non-marginal relay is to operate, that is to say for calls to an operator, the circuit for the supervisory relays includes only one speaking lead. It may therefore be convenient to reverse the operation of these relays so that on an opera-

tor call when the line resistance would in general be less owing to the inclusion of only one speaking lead, both relays are operated and in this case no metering takes place, 5 where as on a call to a subscriber which in view of the fact that the two speaking leads are used in series, would tend to involve a greater resistance, only the non-marginal relay is operated and in this case metering takes place. It would probably be desirable 10 to render the operation more certain by including a fairly high resistance between the battery feeding retard and the associated speaking lead, this resistance being cut out 15 on the operation of the non-marginal relay by which time the marginal relay will have been short circuited. Since answering supervision does not take place over this leg on calls to the operator, this resistance is not included in the circuit and both the supervisory 20 relays will therefore operate. A possible objection to this arrangement is that in case a call is extended over a leaky line, the tendency would be for the current through the 25 supervisory relays to be reduced and in the case of an operator, call when both the supervisory relays should operate, the leak might be sufficient to prevent the marginal relay from picking up, in which case metering 30 would take place when it was not intended. If this chance of trouble were considered serious, it might be overcome by reversing all the battery feed connections so that the supervisory relays were connected to battery 35 instead of to earth. Under these conditions the effect of a leaky line would tend to be to prevent metering when it was really due and the subscriber would not suffer.

The arrangement shown applied in Fig. 8 40 would perhaps be more satisfactory however since there the relays are connected up entirely separately. It will be understood that the two relays could also be connected up in parallel instead of separately as shown in 45 Fig. 8, the essence of the arrangement being that they are connected up in turn so that some kind of timing device, conveniently a slow relay, is required. Moreover, the marginal relay could be arranged to be connected up temporarily instead of throughout the 50 conversation as in the arrangement of Fig. 8, and in this case it is desirable to arrange that the marginal relay is momentarily connected up each time the subscriber's loop is 55 opened so that there is no danger of metering not taking place in case the called party removes his receiver clumsily.

It will be understood also that the arrangement shown in Fig. 8 whereby the relay 60 which is up throughout the dialling period disconnects one terminal of the speaking condensers is in no way bound up with the modified supervisory circuits and could be applied without difficulty to the switches shown in 65 Figs. 1, 2 and 6.

What I claim as new and desire to secure by Letters Patent is:—

1. In a telephone system, a trunk line terminating in a numerical switch, a train of automatic switches controlled from said first switch to set up a connection, non-supervisory equipment in said first switch for feeding battery and ground forward over the two speaking leads respectively to said automatic switches until the connection is set up, and means including a retardation coil and two supervisory relays in said first switch for feeding battery and ground forward over the two speaking leads respectively after the connection has been set up. 70

2. In a telephone system, a plurality of automatic switches, means for transmitting a plurality of series of impulses over the two speaking leads in series to operate said switches to set up a connection, a plurality of supervisory relays, and means for connecting said relays automatically in turn to only one of the speaking leads in the connection set up to control the sending of supervisory signals when the setting operation has been 80 completed. 85

3. In a telephone system, a trunk line terminating in a numerical switch, a train of automatic switches controlled from said first switch to set up a connection, non-supervisory equipment in said first switch for feeding battery and ground forward over the two speaking leads respectively to said automatic switches until the connection is set up, means including one or more supervisory relays in said first switch for feeding battery and ground forward over the two speaking leads respectively after the connection has been set up, a slow-acting change-over relay included in said non-supervisory equipment, and means including said relay for changing the battery feed from said non-supervisory connection to the supervisory connection after the setting operation has been completed. 95

4. In a telephone system, a trunk line terminating in a numerical switch, a train of automatic switches controlled from said first switch to set up a connection, non-supervisory equipment in said first switch for feeding battery and ground forward over the two speaking leads respectively to said automatic switches until the connection is set up, means including one or more supervisory relays in said first switch for feeding battery and ground forward over the two speaking leads 100 respectively after the connection has been set up, a slow-acting change-over relay included in said non-supervisory equipment, means including said relay for changing the battery feed from said non-supervisory connection to the supervisory connection after the setting operation has been completed, and means for maintaining said change-over relay energized during the setting up of the connection in a circuit including the two 105 110 115 120 125 130

- speaking leads in series and a source of energy at the outgoing end.
5. In a telephone system, a trunk line terminating in a numerical switch, a train of automatic switches controlled from said first switch to set up a connection, non-supervisory equipment in said first switch for feeding battery and ground forward over the two speaking leads respectively to said automatic switches until the connection is set up, means including one or more supervisory relays in said first switch for feeding battery and ground forward over the two speaking leads respectively after the connection has been set up, a change-over relay included in said non-supervisory equipment, means including said relay for changing the battery feed from said non-supervisory connection to the supervisory connection after the setting operation has been completed, means for short circuiting said change-over relay during the sending of impulses to improve impulsing, a series relay, and means controlled by said series relay for maintaining said change-over relay energized while it is short circuited.
6. In a telephone system, a trunk line terminating in an incoming selector, a line relay in said selector connected across the speaking leads of said trunk line without battery or ground connections when said selector is in normal position and during the impulsing period, and means operative after the termination of impulse sending for connecting said line relay to only one of the speaking leads of said trunk line.
7. In a telephone system, a plurality of automatic switches, means for transmitting a plurality of series of impulses over the two speaking leads in series to operate said switches to set up a connection, a plurality of supervisory relays, and means including a timing device for connecting said relays automatically in turn to only one of the speaking leads in the connection set up to control the sending of supervisory signals when the setting operation has been completed.
8. In a telephone system, a trunk line terminating in an incoming selector repeater, automatic switches, a line relay in said repeater bridged across the two conductors of said trunk line, means for feeding battery and ground forward over the two conductors of said trunk line in series to said repeater to energize said relay, means for interrupting one conductor of said trunk line to intermittently operate said line relay, means controlled by said line relay for operating said selector repeater to seize an idle one of said switches, and means in said selector repeater for substituting a local ground for one of the trunk conductors whereby the subsequent control of said line relay is controlled over only one trunk conductor.
9. In a telephone system, a trunk line terminating in an incoming selector, a line relay in said selector connected across the speaking leads of said trunk line without battery or ground connections when said selector is in normal position and during the impulsing period, and means operative after the termination of impulse sending for connecting said line relay to only one of the speaking leads of said trunk line and for using the other of said speaking leads for supervisory purposes.
10. In a telephone system, a trunk line terminating in an incoming selector, a line relay in said selector connected across the speaking leads of said trunk line without battery or ground connections when said selector is in normal position and during the impulsing period, a train of automatic switches, means controlled by said line relay responsive to impulses received for successively controlling said switches in said train to complete a connection, and means responsive to the last switch in said train completing its operation for connecting said line relay to only one of the speaking leads of said trunk.
11. In a telephone system, a trunk line terminating in an incoming selector, a line relay in said selector normally connected across the talking conductors of said trunk line without battery or ground connections, means operative responsive to the seizure of said switch for energizing and maintaining said relay bridged across said talking conductors, and means responsive to the termination of a complete series of impulses for rendering said first means inoperative whereby said relay is maintained energized over only one of said conductors while the other of said conductors is used for supervisory purposes.
12. In a telephone system, a trunk line terminating in an incoming selector, a line relay in said selector normally connected across the talking conductors of said trunk line without battery or ground connections, means operative responsive to the seizure of said switch for energizing and maintaining said relay bridged across said talking conductors, means operative responsive to the termination of a complete series of impulses for opening said bridge and for completing a holding circuit for said relay including only one of said conductors, and means in said selector for thereafter transmitting supervisory signals over the other of said conductors.
- In testimony whereof I have signed my name at London, England, this 29th day of June 1926.
- FRANK TENCH.
